UNITED STATES PATENT OFFICE.

ROBERT BROWN, OF MONTROSE, COLORADO.

SPARK-ARRESTER.

1,347,680.

Specification of Letters Patent. Patented July 27, 1920.

Application filed May 24, 1920. Serial No. 383,803.

To all whom it may concern:

Be it known that I, ROBERT BROWN, a citizen of the United States of America, residing at Montrose, in the county of Montrose and State of Colorado, have invented certain new and useful Improvements in Spark-Arresters, of which the following is a specification.

This invention relates to certain new and useful improvements in spark arresters constructed for attachment to the upper end of a chimney to prevent the escape of sparks and live cinders from the chimney with a collection pan for the cinders.

15 A further object of the invention resides in the provision of a combined spark arrester and cowl wherein there is provided a collection receptacle for sparks that are prevented from escape from the chimney, devices being associated with the cowl and functioning when said cowl is partially rotated to clean the receptacle of the sparks and cinders collected therein.

25 With the above and other objects in view, the present invention consists in the novel form, combination and arrangement of parts hereinafter more fully described, and shown in the accompanying drawing, wherein like reference characters indicate similar parts throughout the several views.

30 In the drawing,

Figure 1 is a side elevational view of a combined spark arrester and cowl constructed in accordance with the present invention, the same being shown in operative position upon the upper portion of a smoke stack,

35 Fig. 2 is a front elevational view thereof, partly in section showing the manner of supporting the device upon the upper end of the chimney,

40 Fig. 3 is a horizontal sectional view taken on line III—III of Fig. 2 showing the outlet openings in the bottom of the collection receptacle with the scraper feet for sweeping the cinders to said outlet openings, and

45 Fig. 4 is a fragmentary perspective view of the frame provided with the sweeping feet.

50 Briefly described, the present invention has for its object to provide a combined spark arrester and cowl for attachment to chimneys, the device embodying an elbow

pipe section that is rotatably supported upon the upper end of the chimney with a 55 screen in the outer end to prevent the escape of sparks. A weather vane is associated with said elbow section to effect rotation thereof and is operated in the usual manner by air pressure. A collection pan or 60 receptacle incloses the upper end of the chimney and carries a cylindrical screen which is secured at its lower end to the receptacle and open at its upper end, and spaced from the chimney to provide a clearance for the intermediate positioning of the lower end of the elbow. A skeleton frame is fixed in said elbow and has depending legs provided with scraper feet upon the lower ends thereof that terminate in proximity of the bottom of the collection pan, 65 the partial rotation of the elbow section effecting movement of the sweeping feet relative to the pan to shift the collected cinders therein to openings provided in the 70 bottom of the pan for discharge therefrom.

The device may be readily attached to an ordinary chimney by providing in the upper end 5 of said chimney, a pair of spaced spiders 6 and 7 having the outer ends thereof of angularly bent and secured as at 8 to the chimney 5 while the central body portions of the spiders 6 and 7 are provided with bearing openings as shown in Figs. 2 and 3.

80 The spark arrester and cowl includes a 85 collection pan formed with a circular vertical wall 9 and a bottom wall 10 that incloses the chimney 5 at a point spaced below the upper end thereof. A cylindrical screen section 11 open at its upper end as shown in Fig. 2 has the lower end thereof received in said collection pan and suitably secured inwardly of the vertical wall 9 in contact therewith, the screen section 11 being spaced from the chimney 5 as illustrated.

95 An elbow pipe 12 is rotatably associated with the upper end of the chimney 5 and is provided with a screen closure 13 at the outlet end thereof to prevent the escape of live sparks therefrom. The elbow 12 is supported in inclosing relations with the upper end 5 of the chamber as shown in Fig. 2 by a vertical bearing rod 14 freely extending through the central openings in the spiders 6 and 7 while a block 15 around the rod 14 100 rests upon the upper spider 7 to form a sup-

- port for the elbow. The rod 14 is fixed relative to the elbow 12 and extends through a spider 16 fixed as at 17 to said elbow while blocks 18 secure the rod 14 to the spider 16 so that the rod, spider 16 and elbow 12 move in unison. As shown more clearly in Fig. 1, the rod 14 vertically projects through the elbow 12 as at 14' and has a weather vane 19 secured to the upper end thereof. The pipe 12 with the rod 14 is rotatably supported by the block 15 resting on the spider 7 and by air currents engaging the vane 19, the elbow 12 is rotatably shiftable. In the operation of the device, live sparks entering the elbow 12 will engage the screen 13 and be thrown backwardly and will fall upon the bottom wall 10 of the collection receptacle while the screen 11 prevents the lateral escape of the same.
- 20 In order to provide cleaning devices for the collection pan, a frame structure of the form best illustrated in Figs. 2 and 4 is fixed to the lower end of the elbow 12 and bodily movable therewith, such device embodying a pair of upper and lower bands 19 connected by the vertical legs 20 in the form of flat strips, flatly engaging the outer faces of the bands while the lower ends of the legs 20 are twisted at right angles to the major transverse axis thereof to provide sweeping feet 21. The annular bands 19 are secured within the lower open end of the elbow 12 by the rivets 22, the lower ends of the legs 20 projecting below the elbow 12 with the major axis of the feet 21 extending transversely of the bottom 10 of the collection pan as shown in Figs. 2 and 3. Spaced outlet openings 23 are provided in the bottom 10 of the collection pan as shown in Figs. 2 and 3 so that upon rotation of the elbow pipe 12, the feet 21 will sweep the cinders resting upon the bottom wall 10 to the exit openings 23.
- 45 From the above detailed description of the invention, it is believed that the construction and operation will at once be apparent, it being noted that the operation thereof is continuous, depending upon the air currents operating the weather vane 19, the elbow pipe 12 being rotatably supported upon the spider 7 by the block 15 resting thereon. The scraper feet 21 being fixed relative to the elbow 12 are movable therewith and when the elbow is rotated in either direction, the feet 21 shift the collected cinders upon the pan wall 10 to the opening in the path of movement thereof. As shown in Fig. 2, the lower ends of the feet 21 are slightly spaced from the bottom walls 10 to 60 eliminate the possibility of friction and hindrance to the correct operation of the device.

While there is herein shown and described what is believed to be the preferred embodiment of the invention, it is nevertheless to

be understood that minor changes may be made in the novel form, combination and arrangement of parts without departing from the spirit and scope of the same as herein-after claimed.

What is claimed as new is:

1. The combination with a chimney provided with a rotatable cowl and a cinder receptacle beneath the same with outlet openings in the cinder receptacle, of means carried by the cowl and movable therewith for shifting the cinders to the receptacle openings. 70
2. The combination with a chimney provided with a rotatable cowl and a cinder receptacle beneath the same with outlet openings in the cinder receptacle, of legs depending from said cowl and having lower terminal feet adapted to shift the cinders in the receptacle to the outlet openings. 80
3. A spark arrester comprising in combination with a chimney having spider supports therein, an elbow pipe having a vertical rod fixed therein with the rod rotatably supported upon said spiders, means for effecting rotation of said elbow pipe, a screen for the outer end of the elbow pipe, said elbow pipe inclosing the upper end of the chimney, a cinder receptacle secured to said chimney, a cylindrical screen carried by said receptacle and inclosing the lower end of said elbow pipe, said collection receptacle having spaced openings in the bottom wall thereof and means carried by the elbow pipe and movable therewith for shifting the collected cinders in the receptacle to said openings. 90
4. A spark arrester comprising in combination with a chimney having spider supports therein, an elbow pipe having a vertical rod fixed therein with the rod rotatably supported upon said spiders, means for effecting rotation of said elbow pipe, a screen for the outer end of the elbow pipe, said elbow pipe inclosing the upper end of the chimney, a cinder receptacle secured to said chimney, a cylindrical screen carried by said receptacle and inclosing the lower end of said elbow pipe, said collection receptacle having spaced openings in the bottom wall thereof, legs depending from the lower end of said elbow pipe with the lower ends twisted to provide feet terminating in proximity of said receptacle for shifting the cinders upon the bottom wall thereof to the outlet openings. 100
5. A spark arrester comprising in combination with a chimney having spider supports therein, an elbow pipe having a vertical rod fixed therein with the rod rotatably supported upon said spiders, means for effecting rotation of said elbow pipe, a screen for the outer end of the elbow pipe, said elbow pipe inclosing the upper end of the chimney, a cinder receptacle secured to said 110

- 130

chimney, a cylindrical screen carried by said receptacle and inclosing the lower end of said elbow pipe, said collection receptacle having spaced openings in the bottom wall 5 thereof, means carried by the elbow pipe and movable therewith for shifting the collected cinders in the receptacle to said open-

ings, said means including a pair of annular bands, vertical legs connecting the bands and provided with feet upon the lower end 10 thereof.

In testimony whereof I affix my signature.

ROBERT BROWN
